MILLER REESE HUTCHISON, OF WEST ORANGE, NEW JERSEY, ASSIGNOR TO LOVELL-McCONNELL MANUFACTURING COMPANY, A CORPORATION OF DELAWARE.

DIAPHRAGM-HORN.

1,120,619.

Specification of Letters Patent. Patented Dec. 8, 1914.

Original application filed October 26, 1909, Serial No. 524,762. Divided and this application filed August 26, 1914. Serial No. 858,676.

To all whom it may concern:

Be it known that I, MILLER REESE HUTCHISON, a citizen of the United States, and a resident of West Orange, in the county of 5 Essex and State of New Jersey, have invented certain new and useful Improvements in Diaphragm-Horns, of which the following is a specification.

My present invention relates to horns or 10 signaling devices wherein a diaphragm is vibrated by a rotary cam mounted on a suitable shaft such for instance as the armature shaft of an electric motor. In my prior Patent 923,122, I have disclosed one form 15 of motor, motor support and cam to operate the diaphragm, and in my co-pending application, Ser. No. 524,762, filed October 26th, 1909, of which the present application is a division, I have shown other forms in 20 which I employ such an arrangement of parts that the vibratory motion of the diaphragm may be derived from the armature shaft of an electric motor, with such shaft arranged at an angle to the plane of the dia- 25 phragm instead of parallel therewith. This is particularly desirable, since it permits a compact arrangement of the electric motor within a case which need not extend peripherally outside of the circumference required 30 for inclosing the diaphragm. In the particular form hereinafter described, the motor is arranged with its armature at an acute angle to the diaphragm, and the axis of the shaft is out of alinement with the 35 center of the diaphragm. By means of this arrangement, the center of mass or volume of the motor may be brought close to a perpendicular from the center of the dia- 40 phragm, and at the same time the cam surfaces adjacent to the periphery of a rotor may operate at the center of the diaphragm.

My invention involves other features of 45 importance which will be pointed out in connection with the description of one practical embodiment thereof shown in the accompanying drawing in which the figure is a vertical section longitudinally of the drive shaft, the motor being shown in elevation.

In the drawing the horn or resonator 1, 50 front case 2, peripheral flange 3, diaphragm 4, clamps 5, 6, and cork-like gaskets 7, 8, are of any known construction suitable for the purpose. The wear piece 72, secured to the center of the diaphragm, may be of any

known or approved construction, but is 55 preferably formed for straight line contact with the rotary displacing member. The drive shaft 10 carries a rotary member 70 provided with teeth or projections 76, the latter being projections on a bevel face, 60 preferably cut in accordance with the well-known principles similar to those established for teeth of bevel or crown gears, so that their sliding engagement with the dia- 65 phragm projection 72 will not vary much from line of contact.

The motor may be any suitable rotary motor, though for most purposes I prefer a low voltage direct current, shunt-wound motor, adapted to rotate at high speed and 70 always in one direction, regardless of the polarity of the current supplied thereto. In the form shown, the drive shaft is at an acute angle to the plane of the diaphragm, with its axial projections intersecting at a 75 point eccentric to the diaphragm by an amount approximately equal to the radius of the face cam. Obviously, the eccentricity of the axial projection of the motor shaft may be decreased by decreasing 80 the diameter of the face cam or by tilting the motor to a greater extent, but preferably the center of mass or volume of the motor, lies practically in a line perpendicular to the axis of the diaphragm. The 85 size of the rotary member 70, the angle of inclination of the axis and the eccentricity of the point of intersection of axial projection of shaft and diaphragm are preferably interdependent in order to keep the mass of 90 the motor close to a line perpendicular to the diaphragm passing through the center thereof. By this arrangement the motor may be brought well within the periphery of the dia- 95 phragm clamps 5, 6 and a separate case 73 for the motor may be employed which is also of less diameter than said clamps and is symmetrical with respect to the axis of the horn 1. The teeth or projections 76 on the rotor and the wear piece on the dia- 100 phragm are formed so that the elements thereof produce true contact and are substantially parallel with the diaphragm. Thus the angle of the axis and the angle or bevel of the teeth are interdependent. The rear 105 clamp 6 of the diaphragm involves an important feature of my invention. It carries preferably integral therewith, an arm 74

having an inclined upper surface to which the motor is detachably connected by a bolt 75 passing through a slot 76 shown in dotted lines. This support and connection for the motor should be formed so that adjustment of the rotary member 70 to and from the wear piece 72 on the diaphragm may be effected. In form shown such adjustment is permitted by the slot in the arm and is 10 along a line parallel to the axis of the motor. By reason of the angular mounting of the motor shaft, a given axial adjustment produces a lesser movement of the rotor directly away from the diaphragm than would 15 be the case were the shaft at right angles and therefore finer adjustment is possible. The shell of the motor is not broken away to show the internal construction since this part of the device is standard construction, 20 such as may be obtained in the market. The motor being thus adjustably mounted and movable in a direction at an acute angle to the diaphragm, a set screw for adjusting the armature shaft in respect to the field, may or 25 may not be employed. The motor may be provided with an ordinary thrust bearing for the armature shaft within the boss 78. With this construction the parts may all be assembled and tested without the rear 30 case, the latter being applied over the flange 79 and secured thereto as by screws 80. The inclined arrangement of the drive shaft has the further advantage that the device may be secured in position so that gravity keeps 35 the shaft normally in contact with the rear thrust bearing, thereby insuring uniform extent of overlap of cam and wear piece regardless of any endwise play of the shaft such as is usually provided for to insure 40 free running in small electric motors of the type here contemplated. This tends to make starting easier and more certain as the cam is always at its maximum distance from the diaphragm. It also eliminates the possi- 45 bility of slight endwise chattering of the shaft such as is likely to occur under certain conditions, particularly at starting and stopping when the cam contacts are least harmonious with the natural bodily swing of 50 the diaphragm.

While I have herein fully shown and described, and have pointed out in the appended claims certain novel features of construction, arrangement, and operation which 55 characterize my invention, it will be understood by those skilled in the art that various omissions, substitutions, and changes in the forms, proportions, sizes, and details of the device and of its operation, may be made 60 without departing from my invention.

Having thus described my invention, what I claim as new and desire to secure by Letters Patent, is:—

1. In an alarm or signaling device, a dia- 65 phragm, and mechanical means including a

drive shaft disposed at an acute angle to said diaphragm for vibrating the latter in combination with means for supporting said parts with the center of volume of the driving mechanism close to a line passing 70 through the axis of the horn and the center of the diaphragm.

2. In an alarm or signaling device, a dia- 75 phragm, and mechanical means including an electric motor for vibrating said dia- phragm in combination with means for sup- porting said parts with the motor shaft at an acute angle to the plane of the dia- phragm, and with the center of mass of the motor substantially in a line normal to the 80 diaaphragm at the center of the latter.

3. In an alarm or signaling device, a dia- 85 phragm and mechanical means including an electric motor for vibrating said diaaphragm in combination with means for supporting said parts with the motor shaft at an acute angle to the plane of the diaaphragm, the motor and diaaphragm being proportioned and arranged so that the mechanical driv- ing means does not project peripherally be- 90 yond the circumference of the diaaphragm supporting means, together with a case con- forming to and including all said parts.

4. In an alarm or signaling device, a dia- 95 phragm normally disposed in a substan- tially vertical plane and having a wear- piece, an electric motor having the axis of its shaft disposed at an acute angle to the plane of the diaaphragm and inclined down- wardly and rearwardly from a point above 100 said wearpiece and the center of mass of the motor being substantially in a line nor- mal to the diaaphragm and passing through said wearpiece, and a rotor on the shaft of said motor and having its center above said 105 wearpiece and presenting beveled projec- tions adjacent its periphery for engage- ment with the latter.

5. In an alarm or signaling device, a dia- 110 phragm having a wearpiece, a beveled face cam for vibrating said diaaphragm and a shaft carrying said rotor and disposed at an acute angle to the plane of said diaaphragm, the inclination of said shaft and the angle of bevel of said face cam being propor- 115 tioned to produce line contact between cam and wearpiece.

6. In an alarm or signaling device, a dia- 120 phragm having a wearpiece, a rotor present- ing cam projections for engagement with said wearpiece to vibrate said diaaphragm, a shaft supporting said rotor and disposed at an acute angle to the plane of said dia- phragm, a motor for rotating said shaft the center of mass of said motor being sub- 125 stantially in a line normal to said dia- phragm and passing through said wearpiece and the inclination of said shaft and the size of said rotor being interdependent.

7. In an alarm or signaling device, a dia- 130

- phragm normally disposed substantially in a vertical plane, a motor having its axis inclined downwardly and rearwardly from a point above the center of said diaphragm, a 5 rotor driven by said motor for vibrating said diaphragm and said motor having a thrust bearing for the rear end of said shaft and against which said shaft is retained by gravity.
- 10 8. In an alarm or signaling device, a diaphragm, a drive shaft presented endwise to said diaphragm and adjustable in a direction at an acute angle to said diaphragm, and a rotor carried by said shaft for vibrating said diaphragm.
- 15 9. In a horn or signaling device, a diaphragm, a diaphragm clamp having a slotted bracket integral therewith and presenting the downwardly and rearwardly inclined 20 upper face, and an electric motor mounted on said bracket and adjustable along said inclined face.
- 25 10. In an alarm or signaling device, a diaphragm normally disposed substantially in a vertical plane, a diaphragm clamped for engagement with the peripheral portion of said diaphragm and having an arm extending rearwardly therefrom and presenting a downwardly and rearwardly inclined 30 upper face, an electric motor mounted on the inclined upper face of said arm and having its center of mass substantially in a line at right angles to the diaphragm at the center of the latter, means for adjusting 35 said motor bodily toward and from said diaphragm and a rotor carried by the armature shaft of said motor and disposed above the center of said diaphragm and present-
- ing beveled cam projections for engagement with the diaphragm substantially at the 40 center of the latter.
11. In an alarm or signaling device, a diaphragm, a diaphragm clamping member having a rearwardly projecting annular flange and an arm integral with said flange and 45 within the periphery of the latter and projecting rearwardly therefrom, and having a slot extending lengthwise thereof, a high speed, rotary, electric motor, means extending through said slot for detachably and 50 adjustably securing said motor to said arm, and a thin sheet metal case inclosing said motor and said arm and telescoping with and detachably secured to said flange.
12. In an alarm or signaling device, a diaphragm, a diaphragm clamping member having an arm integral therewith and projecting rearwardly therefrom, adjacent one 55 edge only of the diaphragm and having a slot extending lengthwise thereof, a high speed, rotary, electric motor having its shaft presented endwise to said diaphragm, means 60 carried by said motor for vibrating said diaphragm, means extending through said slot for detachably and adjustably securing said 65 motor to said arm, and a thin sheet metal case inclosing said motor and arm and detachably secured to said clamping member.

Signed at West Orange in the county of Essex and State of New Jersey this 24th 70 day of August, 1914.

MILLER REESE HUTCHISON.
